COMPRESSION EXTRACTOR

Thomas S. Watson, Milwaukee, Wis., assignor to
Huebsch Manufacturing Company, Milwaukee,
Wis., a corporation of Wisconsin

Application October 11, 1944, Serial No. 558,255

2 Claims. (Cl. 100—50)

1

The invention relates to compression extractors and more particularly to that type of extractor in which fluid pressure exerted against a flexible diaphragm compresses the material operated upon between said diaphragm and an apertured casing to extract liquid from said material. Extractors of this kind have been found to have advantages for extracting water from laundry and also according to this invention are used for reducing the liquid content of brewery mash, so that the waste mash solids may be used as a feed product. These extractors may also be used in other arts or processes where reduction of the liquid content of a compressible material is desirable.

The object of the invention is to provide a new and improved arrangement for expeditiously carrying out the extraction cycle especially where large quantities of material such as brewery mash are being handled.

The invention further consists in the several features hereinafter set forth and more particularly defined by claims at the conclusion hereof.

In the drawings:

Fig. 1 is a vertical sectional view taken on the line 1—1 of Fig. 3;

Fig. 2 is a detailed vertical sectional view taken on the line 2—2 of Fig. 3;

Fig. 3 is an elevation view of a tilting type of compression extractor associated with a loading means therefor and with controls used in its cycle of operations, some parts being shown in section;

Fig. 4 is a detailed vertical sectional view through a portion of the cover.

In Figs. 1 to 3, inclusive, I have shown a structure more particularly designed for extracting liquids from semi-solid materials, such as brewery or distillery mash, which has a high moisture content but which contains valuable by-products.

Referring to Fig. 1, the numeral 41 designates a casing or container having a grooved rim 42 at its top and an opening 43 in its bottom connected by a pipe 44 with a drain and supply pipe fitting 45. The container 41 has a wall portion 41' provided with trunnions 46 journalled in a frame 47, so that the container can be tipped to discharge its load. The fitting 45 has a tapered flexible rubber coupling 48 within which the tapered end of the pipe 44 fits when the casing is in operative position but which permits automatic release of this connection when the container is tipped to the dotted line position shown in Fig. 3.

A bag 49 of rubber composition or other suitable flexible material fits within the container, and its rim 50 is adapted to fit in the groove in the rim 42, and it is clamped in this groove by a clamping ring 51 secured to the rim 42 by screws or other suitable fastening means, said ring 51, forming the base of a tubular casing extension 52. This casing extension 52 has an apertured wall

2

portion 53 spaced from the wall portion 41' to provide a temporary drain chamber 55 having a delivery opening 56. The wall portion 53 has the top rim 57 which has an annular recess 58 formed therein in which an endless rubber tube 59 is mounted, said tube when inflated with pressure fluid acting on said rim 57 and a ring 60 secured to the cover 61 (see Fig. 7) by screws 62 to prevent the escape of fluid from the joint between the cover and the casing. Fluid pressure is applied to the tube 59 by connection through a pipe 62 with the pipe 44, so that when the high pressure fluid is introduced into this pipe to raise the bag 49, it will also cause the tube 59 to exert a sealing pressure as above described.

The cover 61 has a top portion 63 spaced from the container and associated with an apertured liner member 64 suitably spaced from said top portion by spacers 64' and having an edge clamped with the ring 60 to the cover by the screws 62'. As the solid particles of the spent mash are relatively fine or small, the apertured portions of the casing 52 and the cover member 64 are covered with a filter cloth, screen, or other filtering element 66, that for the extension being secured in position by spaced clamping rings 67 and screws 68 while that for the cover 61 being secured between the liner 64 and the ring 60.

In Fig. 3, the cover 61 has a semi-cylindrical locking flange 70 similar to the flange 71 shown in Fig. 1 and engageable with the rim 55' of the wall 41', and the casing has a semi-cylindrical locking flange 71 shown in Fig. 1 engageable with the top portion of the cover 61 to hold the cover in closed position or permit its sliding movement to open position on fixed rails 72 suitably mounted on the frame 47, said cover having the wheels 73 riding on said rails 72. As shown in Fig. 3, each locking flange 70 and 71 extends around one-half of the top of the container.

For charging the casing I have shown a hopper 74 having a tubular filling extension 75 entrance to which is controlled by a butterfly valve 76 and exit from which is controlled by a shut off of any suitable construction but preferably of the form shown in Fig. 2 in which an externally controlled rubber diaphragm valve 77 is used to shut off the passage of the semi-fluid mash between said diaphragm and the wall 78 of a delivery spout 79.

The pipe fitting 45 has a valve 80 controlling passage of the operating fluid from the pipe 45 to a drain passage 81 and a valve 82 controlling passage of the high pressure operating fluid from the supply pipe 83.

As shown in Fig. 3, the valves 80 and 82 are of the rotary type, normally closed by a spring 84 and opened by an electrically operated solenoid 85 whose supply circuit connections include a suitable electrically operated timing switch 86.

whose operation is controlled by a start and stop switch 86.

For operating the valve 76 I show its lever arm 87 operatively connected to the plunger or piston rod 88 of a double acting hydraulic motor cylinder 89 whose hydraulic circuit 89' is controlled by a four way valve 90 which is closed by a spring 91 and opened by an electrically operated solenoid 92 whose supply connections include the timing switch 86.

For operating the valve 77 I show a reversible rotary hydraulic motor 93 carrying a gear 94 meshing with a gear 95 on an internally threaded shaft or nut 96 in which a screw shaft 97 secured to the valve 77 is mounted, so that rotation of said nut will cause a lengthwise movement of the shaft 97 and consequently the central portion of the diaphragm 77 secured thereto to move it into or out of closing position. The operation of the hydraulic circuit 93' for the motor 93 is controlled by a four way valve 98 which is closed by a spring 99 and opened by an electrically operated solenoid 100 whose supply connections include the timing switch 86.

For moving the cover to open or closed position I provide a double acting hydraulic motor cylinder 101 having its operating piston 102 connected to the cover and whose hydraulic circuit 101' is controlled by a four way valve 103 which is closed by a spring 104 and opened by an electrically operated solenoid 105 whose supply connections include the timing switch 86.

For tipping the loaded casing I mount a gear 106 on one of the trunnions 46 and mesh with a segmental gear 107 pivoted on a shaft 108 and operated by a crank arm 109 operatively connected to the plunger or piston rod 110 of a double acting hydraulic motor cylinder 111 whose hydraulic circuit 111' is controlled by a four-way valve 112 which is closed by a spring 113 and opened by an electrically operated solenoid 114 whose supply connections include the timing switch 86.

The hydraulic supply circuit 115 in which the valves 90, 98, 103, and 112 are disposed includes a suitably driven pressure pump 116 and a sump or feed chamber 117.

All the solenoids have one of their terminals connected with one electrical supply conductor 118 while the other conductor 119 connects with the switch 86 which through the conductors 120, 121, 122, 123, 124, and 125 selectively distributes the supply current to the solenoids 85, 92, 100, 105, and 114.

In its tipped position the casing may discharge the dehydrated material into any suitable receptacle such as the hopper 126.

With the above described structure the preferred cycle of operations is, as follows: While the casing 41 is in inverted position and the contents are being discharged therefrom, the valve 77 is closed and the valve 76 then opened to allow the material from the hopper 74 to fill the extension 75. Thereafter, the switch 86 causes the solenoids 114 and 92 to operate the valves 112 and 98 so as to cause the motor 111 to swing the casing 41 to upright operative position and close the valve 76. With the casing 41 in operative position the switch 86 closes the circuit to the solenoid 100 to operate the valve 98 so as to supply operating fluid to the motor 93 to rotate the same and open the valve 77 and to keep this open until the casing 41 receives its charge. Thereafter, the spring 99 moves the valve 98 to a position to reverse the motor 93 and move the

valve 77 to closed position. As the valve 77 closes, the switch 86 closes the circuit to the solenoid 105 which operates the valve 103 to cause the motor 101 to move the cover 61 over on top of the casing to a closed and locked position. Thereafter, the switch 86 closes the circuit through conductor 120 and its solenoid 85 to open the valve 82 (the valve 80 then being closed) and allow pressure fluid to enter the space between the bottom of the casing 41 and the bag 49 and force said bag together with its contents upwardly, thus squeezing or compressing said contents between the bag and the apertured walls 53 and the top 64 of the cover so as to force the liquid content of material through the filtering elements 66 and into the drainage space 55. After a predetermined period the valve 82 is closed by the spring 84 and the switch 86 closes the circuit through conductor 121 and its solenoid 85 to open the drain valve 80 to allow the pressure fluid to drain out of the casing 41 through the pipe 81. Thereafter, the motor 101 is operated through the switch 86, solenoid 105, and valve 103 to move the cover 61 to open position, and then the motor 111 is operated through the switch 86, solenoid 114, and valve 112 to swing the casing 41 to dumping position and the dehydrated material is discharged therefrom into the hopper 126 while the valve 77 is closed through the operation of the motor 93 and the valve 76 is opened through the operation of the motor 89 to fill the extension 75. Thereafter, the cycle is repeated.

The above arrangement provides an expeditious extraction of a considerable amount of the liquid content of spent mash or similar materials at a cost to make the saving of the solid contents of such materials as a by-product profitable.

It will be noted that the complete casing is formed by the lower part such as 41 and by an upper part or extension 52 and that the bag 49 is anchored or clamped at its rim between these two parts or substantially medially of the complete casing.

I desire it to be understood that this invention is not to be limited to any particular form or arrangement of parts except insofar as such limitations are included in the claims.

What I claim as my invention is:

1. In a device of the character described, the combination of a compression extractor mounted for tilting movement and having connections at its lower end with a source of pressure fluid supply and a drain connection, valves for controlling said pressure fluid source connection and said drain connection respectively, means for tilting said extractor to an inverted discharge position and to a filling position, a removable cover for said extractor, means for moving said cover into and out of closing position, filling means for said extractor comprising a chamber having an outlet valve, means for operating said outlet valve, and timing means for controlling the operation of said last named valve, said cover moving means, said extractor tilting means, and said pressure supply valve and drain valve in sequence.

2. In a device of the character described, the combination of a compression extractor mounted for tilting movement and having connections at its lower end with a source of pressure fluid supply and a drain connection, valves for controlling said pressure fluid source connection and said drain connection respectively, means for tilting said extractor to an inverted discharge position and to a filling position, a removable cover for

said extractor, means for moving said cover into and out of closing position, filling means for said extractor comprising a chamber having an inlet valve and an outlet valve, means for operating said inlet and outlet valves, and timing means for controlling the operation of said last named valves, said cover moving means, said extractor tilting means, and said pressure supply valve and drain valve in sequence.
